UNITED STATES PATENT OFFICE.

F. W. MALLETT, OF NEW HAVEN, CONNECTICUT, ASSIGNOR TO HIMSELF
AND GEORGE COOK, OF SAME PLACE.

IMPROVED MACHINE FOR MAKING SEWING-MACHINE NEEDLES.

Specification forming part of Letters Patent No. 85,682, dated January 5, 1869.

To all whom it may concern:

Be it known that I, F. W. MALLETT, of the city and county of New Haven, State of Connecticut, have invented a new and useful Improvement in Machines for Making Sewing-Needles; and do hereby declare that the following is a general description thereof, reference being had to the accompanying drawings, making part of this specification, of which—

Figure 1 represents a front-side elevation; Fig. 2, a rear-side elevation; Fig. 3, a plan or top view; Fig. 4, an elevation of feed end; Fig. 5, an elevation of opposite end; and Fig. 6, a transverse section of said machine, taken on line $x' x'$ of Fig. 1. Figs. 7, 8, and 9 are views of one of the progressive rollers, as removed from the machine, showing the operative mechanism for taking up, carrying, and delivering the needle-blanks to the next progressive roller, as well as to the parallel carrying-screws.

This invention relates to an improvement in the class of self-acting machines for making needles; and consists of a peculiar combination of mechanism by which two sewing-needles are made by one operation, and at one and the same time, in the following manner: In the first place, the wires or blanks, being cut to the desired length for two needles, are thrown into a hopper, which has, in connection with the same, a feeding device, which conveys one blank at a time to the first set of a series of progressive carrying-rollers, which take up the blanks in turn and carry them from one to the other; and while being so carried by the rollers, the said needle-blanks are stamped, the eyes punched, and the eyes tested by a feeler, which will detect the blank not properly eyed, and will stop the feed mechanism for its removal; second, the blanks being properly stamped, eyed, and burnished, the last of the series of progressive rollers will deliver the blank, by means of a conductor, to two parallel rotating carrying-screws, which carry the blank over needle-pointing grind-rollers, the needle-blanks at the same time being rotated during the operation of pointing the same by an endless friction-belt; third,

the stamping, eyeing, and pointing being performed, the said parallel screws will introduce the blank to two other parallel rotating carrying-screws, which aid in carrying the said blank (which is in like manner rotated by endless belts) up against a cutter-wheel, which cuts the blank between the eyes, separating the needles, at the same time removing the burr from the needle-heads, and, finally, the said screws discharge the finished needles at the end of the machine.

Thus I produce an automatic machine for making two needles by one operation and at one and the same time.

Having described the nature of my invention, I will now describe its construction and operation.

In the said drawings, A indicates the driving-shaft, carrying a bevel-gear, B, worms CC, spur-gear D, and pulley E, forming part of and operating the needle-machine. The bevel-gear B engages with the bevel-gear B', rotating the shaft F, which carries on its inner end a gear, G, which engages with a gear, H, on the end of the feed-shaft I. Said feed-shaft carries a double-acting cam, K, which operates the feed mechanism, consisting of a forked arm, L, (embracing the shaft I,) a pin, M, projecting from said arm, a coiled spring, N, a lever, O, and bifurcated feed-plate P, which receives the needle-blanks alternately from the hopper Q, and delivers the same to the progressive rollers R R, &c. (See Figs. 1 and 3.) These progressive carrying-rollers rotate on their shafts S S, which are stationary, and are sustained in a bearing, T, on the table U of the machine. Said rollers carry gears V V, which engage with carrying-gears W W, and with gears X X on the feed-shaft I, by means of which motion is imparted to the series of progressive carrying-rollers, as shown in Figs. 1 and 3. The said carrying-rollers are furnished with catches Y Y and springs Y' Y', and are operated by cams Z on their stationary shafts, (see Figs. 7, 8, and 9,) which serve to throw out the catches for reception of the needle-blanks, and for delivery of the same.

a is the stamp, which falls on the block b,

for stamping the blank preparatory to punching the eyes in the same. This stamp is operated by a cam, *c*, on the end of the shaft *d*, and a spring, *e*, attached to the case *f*, said shaft *d* being rotated by the shaft *F* and intermediate gears *d¹* *d²*.

g is the punch, and *h* a perforated block, for punching the eyes in the blank needles, and it consists of a sliding bar, *i*, with punches *j*, said sliding bar being operated by an eccentric, *j'*, attached to the shaft *d³*, as shown in Figs. 1 and 6.

k is the detector, consisting of a long bar, *l*, swung on a pivot attached to the bearing *T*, and having on its inner end an arm, *m*, surmounted by points or feelers *n*, which enter the eyes of the needle-blank, and on its outer end the catch *o*, so that when a blank is not properly eyed the end *m* of the detector will be borne down by the blank and the catch *o* raised, which will catch and stop the feed-plate *P* until the imperfect blank is removed.

p p are the buffers, whose shafts are belted at *q* to the counter-shaft *r* below the table *U* of the machine, the purpose of these buffer-wheels being to remove the burr from the eyes of the blanks, and burnish the same after the punching operation.

s s are conductors, which guide the needle-blanks delivered by the progressive rollers to the parallel rotating carrying-screws *t t*. These screws carry the blanks over and on a double set of grinding, pointing, and finishing rollers, *u v*, on which the extreme ends of the needle-blanks are pointed and burnished, the said blanks being rotated in their passage by an endless friction-belt, *w*, having a tightener composed of pawl *x* and a ratchet-wheel, *y*, (see Fig. 3,) said belt being driven by connections with the main shaft *A*, consisting of the shafts *z z*, worm-gears *a' a'*, and worms *C C* on the said main shaft, while the carrying-screws are connected with said main shaft by a train of gears, *c' c'* and *D*, as shown in Fig. 5.

e¹ e¹ are another set of parallel carrying-screws, with friction-belts *e² e²*, for rotating the needle-blanks, placed on opposite sides of the carrying-screws *t t*, for the purpose of aiding the screws *t t*, by additional bearings, to hold the blanks during the operation of separating the needles and polishing the needle-heads by the cutter-wheel *f'*. Furthermore, the threads of these rotating carrying-screws *e¹ e¹* are of a finer pitch than the screws *t t*, for the purpose of deflecting the blank from a straight line, thereby affording the cutter-wheel *f'* an opportunity to cut and polish the heads of the needles; and, finally, the said

screws, with the screws *t t*, deliver the finished needles at the end *g'* of the machine.

Having described my invention, what I claim as new, and desire to secure by Letters Patent, is—

1. The series of progressive carrying-rollers *R R*, each provided with a holding device, *Y Y, Y' Y'*, *Z*, for holding the wires or needle-blanks in position during the operations of stamping, eyeing, and removing the burr from the eyes of the blanks, substantially as described and set forth.

2. The detector *k l m o*, with eye-feelers *n n*, in combination with the reciprocating feed *p*, for detecting the eyeless blanks and stopping the feed, substantially as set forth and specified.

3. The feed mechanism *K L M N O P*, in combination with the progressive carrying-rollers *R R*, substantially as and for the purposes described and set forth.

4. In combination with the progressive carrying-rollers *R R*, the stamping-press *a* and *b*, and punch *g, j, j*, and *h*, substantially as and for the purposes specified and set forth.

5. In combination with the progressive carrying-rollers *R R*, the buffers *p p*, for removing the burr from the eyes of the blank needle, after stamping and punching the same, substantially as set forth and described.

6. In combination with the progressive carrying-rollers *R R*, the parallel rotating carrying-screws *t t* and *e¹ e¹*, for carrying and holding the needle-blanks in position during the operations of grinding and pointing the said blanks on the rollers *u u* and *v v*, and separating the needles by the cutter-wheel *f'*, substantially as set forth and described.

7. In combination with the progressive carrying-rollers and carrying-screws, the friction-belts *e² e²* and *w*, with pawl *x* and ratchet *y*, for rotating the needle-blank in its passage while carried by the rotating screws, substantially as and for the purposes described and set forth.

8. The improved automatic or self-acting machine herein described, constructed, arranged, and operating so as to feed and present the wires or needle-blanks for action of its operative parts, whereby the needles (two at a time) are finished and discharged from the machine, substantially as described and set forth.

In testimony whereof I have hereunto set my signature this 6th day of November, A. D. 1868.
